ATTORNEY

UNITED STATES PATENT OFFICE.

BRANTLEY P. JOINER, OF FLORENCE, ALABAMA.

STOCK-CAR.

SPECIFICATION forming part of Letters Patent No. 276,595, dated May 1, 1883.

Application filed December 21, 1882. (No model.)

To all whom it may concern:

Be it known that I, BRANTLEY P. JOINER, of Florence, in the county of Lauderdale and State of Alabama, have invented certain new and useful Improvements in Stock-Cars, of which the following is a full, clear, and exact description, reference being had to the accompanying drawings, and to the letters of reference marked thereon.

10 My invention relates especially to railway-cars employed for transporting live stock, and has for its object the provision of simple, cheap, and effective means whereby food and water may be supplied to the stock without removing from the car.

To attain this end my invention consists essentially in employing two transversal troughs suspended within the car, upon each side thereof, by means of cords or chains attached thereto and passing upward to a winding-shaft or over pulleys to a winding-shaft near the bottom of the car, upon the exterior thereof. Said troughs are arranged to receive the food and water, the corn, oats, or other grain being placed within the troughs and elevated to the top of the car, and the water-trough being filled through suitable connecting-pipes located at the end of the car and adapted and arranged to have connection with the road-tanks.

20 The troughs may be elevated at the same time, containing the feed, and lowered only when needed, being entirely out of the way of the stock while loading and unloading, the feed being entirely out of the reach of the stock, and when consumed may be replenished either at the side of the car or at the top. When not in use for transporting cattle, the troughs may all be elevated out of the way, the car being available for any kind of freight. The lowering and hoisting mechanism is so arranged that one man can easily operate it and attend to the needs of an entire train-load of stock with ease and dispatch.

In the drawings, Figure 1 is a perspective view of my improved stock-car, and Fig. 2 is a vertical sectional view at line $x-x$ of Fig. 1.

Like letters of reference, wherever they occur, indicate corresponding parts in both figures.

My improved car may be made entirely new, or any of the ordinary cars now in use may be

fitted with my device. The body of the car may be made with a frame and slats, in the usual manner. Within the car, at each extremity thereof, are affixed guide-strips A, passing at an angle from the bottom to the top of the car. End and side guides, a , may also be affixed, if required, and central guides, A'. At a suitable height above the floor of the car cross-supports B extend from the sides of the car to the upright guides A and A'. 60

C' are grain and water troughs extending the entire length of the car, and of such a capacity as to hold twelve to fifteen bushels of grain each. Affixed to the extremity of each of said troughs is a rope or chain, D, passing to the top of the car and around a longitudinal shaft, E, being attached thereto. These shafts may be made solid, or of metal pipe, as shown, the latter construction rendering them light, while sufficiently strong. 70

At one end of shaft E is located a pawl, F, and ratchet-wheel G, a square hub, e , being provided for a removable crank, H.

I is a water-pipe with two branches, extending to the interior of the car, at each side thereof, in such a manner as to conduct water from the road-tanks to the interior of the car when required. 75

Shaft E may be placed at the bottom of the car instead of at the top, chains D passing 80 therefrom over suitable pulleys, J, at the top of the car, and thence to the troughs.

When constructed and arranged in accordance with the foregoing description, one trough upon each side of the car may be filled with 85 grain and elevated to the top of the car, out of the way of the cattle or stock, and the second brought up at the side of it. When it is desired to feed the stock the crank is applied to the shaft, the pawl thrown back, and the trough lowered until it rests upon the supports B. After the stock have eaten sufficient grain said trough may be elevated and the second trough lowered and filled with water by means of the supply-pipe at the end of the car. 90

Having now fully described my invention, what I claim as new therein, and desire to secure by Letters Patent, is— 95

1. In a stock-car of the character herein specified, the combination, with the body there- 100

of, of the longitudinal troughs C and C', adapted and arranged to be supported at the top of the car, side by side, as set forth, or lowered singly to a common support near the floor of the car, substantially as shown and described.

2. In a stock-car of the character herein specified, the combination, with the troughs C and C', adapted and arranged to be supported at the top of the car, side by side, as set forth, of the slanting guides A and cross-supports B, substantially as shown and described.

3. In a stock-car of the character herein

specified, troughs C and C', guides A and A', shafts E, provided with pawl F and ratchet-wheel G, chains or cords D, crank H, and water-supply pipe I, the whole combined and arranged to operate substantially as shown and described.

In testimony that I claim the foregoing I have hereunto set my hand in the presence of witnesses.

BRANTLEY P. JOINER.
